Fig. 5.

Fig. 1 is a perspective view of a magnetic holder for an automobile gasoline cap embodying my new design; Fig. 2 is a front elevational view of the same; Fig. 3 is a side elevational view of the same; Fig. 4 is a top plan view; and Fig. 5 is a bottom plan view.

The dominant features of my design reside in the combination of a combined clamp and cube having four spaced parallel magnetic elements projecting from the free end of the cube, all as shown.

I claim:

The ornamental design for a magnetic holder for an automobile gasoline cap, substantially as shown and described.
